US00D956099S

(12) United States Design Patent (10) Patent No.: US D956,099 S
(45) Date of Patent:  Jun. 28, 2022

(54) DISPLAY SCREEN OR PORTION THEREOF WITH GRAPHICAL USER INTERFACE

(71) Applicant: Google LLC, Mountain View, CA (US)

(72) Inventors: Kevin Gaunt, San Francisco, CA (US); Andrew Schoneweis, Sunnyvale, CA (US); Chia Cheng Chen, San Francisco, CA (US); Jonathan Gaiser, Sunnyvale, CA (US); Nick Franchi, San Francisco, CA (US); Corine Yang, Redwood City, CA (US)

(73) Assignee: GOOGLE LLC, Mountain View, CA (US)

() Term: 15 Years

(21) Appl. No.: 29/818,111

(22) Filed: Dec. 7, 2021

Related U.S. Application Data

(62) Division of application No. 29/689,864, filed on May 2, 2019, now Pat. No. Des. 940,755.
